(57) **CLAIM**

The ornamental design for a footrest exercise apparatus, as shown and described.

DESCRIPTION

FIG. 1 is a perspective view of the footrest exercise apparatus in a position of use.

FIG. 2 is a perspective view of the footrest exercise apparatus of the invention.

FIG. 3 is a front elevational view of the footrest exercise apparatus of the invention.

FIG. 4 is a rear elevational view of the footrest exercise apparatus of the invention.

FIG. 5 is a right side elevational view of the footrest exercise apparatus of the invention.

FIG. 6 is a left side elevational view of the footrest exercise apparatus of the invention.

FIG. 7 is a top plan view of the footrest exercise apparatus of the invention; and,

FIG. 8 is a bottom plan view of the footrest exercise apparatus of the invention.

The broken lines of FIG. 1 illustrate environmental matter and form no part of the claimed design.
